FLEXIBLE DISPENSING BOTTLE

Louis L. Lerner, Chicago, Ill., assignor to The Gillette Company, Boston, Mass., a corporation of Delaware

Application January 6, 1958, Serial No. 49,145

Term of patent 14 years

(Cl. D58—6)

Fig. 1 is a front elevational view of a flexible dispensing bottle embodying my new design;

Fig. 2 is a side elevational view thereof; and

Fig. 3 is a cross-sectional view thereof taken on the line 3—3 of Fig. 1.

The rear and side, not shown, are the same as the front and side, respectively, shown.

I claim:

The ornamental design for a flexible dispensing bottle, as shown and described.
